TOY BUILDINGS

Joseph L. Bonanno, Madison, N. J., assignor to The Lionel Corporation, New York, N. Y., a corporation of New York

Application August 1, 1951, Serial No. 239,682

6 Claims. (Cl. 46—12)

The present invention relates to toy buildings and is more particularly directed toward toy buildings suitable for use along the right of way of toy electric railroads. The present invention contemplates toy buildings suitable for such uses and constructed in such a way that the parts may be inexpensively manufactured and readily assembled.

The toy buildings made in accordance with the present invention are strong, sturdy devices, suitable for long continued use for the purposes intended. The present invention contemplates toy buildings for these purposes wherein a base or support made of metal or of plastic carries a house-forming body which is easily secured to it in definite position. The body is a piece of molded plastic material of suitable color and is provided with contrasting trimming such as windows, roof and doors, these parts being arranged for inexpensive manufacture and easy assembly. The base and house body are secured together by conducting rods which also serve as supports for wiring clips.

Other and further objects will appear as the description proceeds.

The accompanying drawings show, for purposes of illustrating the present invention, one embodiment in which the invention may take form, together with modifications of certain parts, it being understood that the drawings are illustrative of the invention rather than limiting the same.

In the accompanying drawings:

Figure 1 is a perspective view of a toy building from the front with the door closed;

Figure 2 is a fragmentary perspective view of the building body with the roof removed to show wiring;

Figure 3 is an exploded side elevational view showing the principal parts entering into the assembly of the toy building;

Figure 4 is a top plan view of the toy building with a portion of the roof broken away;

Figure 5 is a horizontal sectional view through the body part of the toy building taken on line 5—5 of Figure 6, showing windows and doors;

Figure 6 is a vertical sectional view taken on the broken line 6—6 of Figure 5;

Figure 6a is a fragmentary view similar to Figure 6 with certain parts reversed;

Figure 7 is a fragmentary view taken on the line 7—7 of Figure 5;

Figure 8 is an inverted plan view at a smaller scale illustrating the base; and

Figure 9 is a fragmentary sectional view showing a modified form of base.

The toy building illustrated herein is designed to simulate in appearance the watchman's shanty ordinarily placed alongside the right of way of regular railroads; and is designed to accommodate a lamp and a remote controlled device such as a whistle. If desired, the lamp may be omitted, or other current consuming devices employed instead of the whistle, for example, an automatic door opening mechanism and gateman as shown in my application, Serial No. 239,681, filed concurrently herewith, now Patent No. 2,688,819.

The toy building shown in Figures 1 through 8 of the drawings employs a molded insulating base 10 of suitable configuration, a molded-plastic, house body-forming

2

member 11 generally in the form of an inverted box-like unit, a roof-forming member 12, a door 13 and windows 14.

The base 10, shown in these figures of the drawings, has a flat upper surface indicated at 15, of the same configuration as the bottom edge of the body-forming unit 11. The base is centrally apertured as indicated at 16 and a remote controlled, motor operated whistle unit designated generally at 17 is secured to the base from below, as for example by soft rubber cushions 18 glued to the base and the whistle body. The motor 19 of the whistle projects up through the opening 16 and is concealed by the house body. The wiring terminal leads for the motor include apertured lugs 20, 21. The base 10 is also provided with a wiring opening 22 and with four pin receiving recesses 23 at the corners of the flat area 15. The base is also apertured as indicated at 24 and 25 for securing rods to be described, and at 26 to provide a pintle opening for the door.

The house body member 11 is a single molding, preferably made of white plastic material, and provided with surface treatment such as clapboards to simulate the watchman's shanty. It has a front wall-forming portion 30 provided with a door opening 31, a rear wall-forming portion 32 provided with a window opening 33, a side wall portion 34 provided with a window opening 35, and an opposite wall 36 provided with an extension 37 to simulate the door tool box. At the top of the side walls 30, 32, 34, and 36, the body member has a top ceiling-like plate 38 which stiffens the plastic molding. This ceiling-like plate is apertured as indicated at 39 and 40, spaced the same as the holes 25 and 24 in the base. It is also provided with a relatively large diagonally disposed opening 41 with an auxiliary wiring hole 42 above the hole 22, with a third hole 43 similar to the holes 39 and 40 and with clip alignment ribs 45. At the front and rear ends, the walls 30 and 32 extend upwardly above the plate 38 to provide gable-like extensions 46 and 47. The rear extension is provided with holes 48a, 48b, 48c for wires.

The window openings 33 and 35 are provided with discontinuous flanges 49 which face outwardly and form stops against which the window units 14 are brought. These flanges 49 are cut away at the sides to permit passage of hook-like members 50 on the window units through to the rear surface of the side walls of the body member. These hook-like members are sufficiently flexible to be forced into place and snap outwardly past reversely beveled ridges 51 provided in the inner walls of the body molding. The windows are preferably of a plastic of contrasting color to that employed on the body member.

The lintel over the door opening has a downwardly opening recess 52. The bottom of the body member 11 has four downwardly extending pins 53 disposed in the same manner as the recesses 23 in the base. In assembling the base, body member and door, it is merely necessary to place the door in the door opening with its upper pin 54 in line with the recess 52 and then place the body member with the door in position on the base so that the pins 53 enter the recesses 23 and the pin 55 at the bottom of the door enters the recess 26. This effectively locates the body relative to the base and provides for the hinging of the door.

In order to secure the body member to the base and provide wiring connections for the motor or other current consuming device, metal rods 60, 61 having heads indicated at 62 are passed up through the terminal members 20 and 21, the holes 24 and 25 in the base and the holes 39 and 40 in the top of the body member. These rods protrude slightly above the top of the body member as can be seen from Figure 6 of the drawing. The rods receive fastening devices 63 and 64 which are in the form

of spring members having prongs 65 to engage the surface of the rod and wire fastening clips 66 and 67, respectively. The members 63 and 64 therefore securely hold the body against removal from the base. As indicated in Figure 6a the rods may be inverted and the clips at the bottom.

The roof member 12 is also made of plastic material, preferably of a contrasting color to that of the body. It has a V-shaped cross-section as indicated in the drawings and is provided with webs 70 which fit inside the gable-forming extensions 46 and 47 as it rests in place.

The wiring connections for the propulsion device or other current-consuming device connected between the rods 60 and 61 are preferably made in the chamber above the house body-forming member and under the roof, the wires being brought in to the clips 66 and 67. One of the wires such as 80 passes through hole 48a and fastens to clip 66. The other wire 81 goes through hole 48c and fastens to spring clip 67. Alternatively, the wires may be brought up through the base and house by passing them through the aligned holes 22 and 42, or may be connected to clips at the bottom as in Figure 6a.

Where it is desired to provide an illuminated house, a lamp 90 and lamp socket 91 may be secured to a leaf spring 92 mounted underneath the clip 67 as indicated in Figure 2. The lamp normally projects down through the opening 41 in the top of the body member. The return wire for the lamp socket is indicated at 93, is connected with another clip 94 held in place by a short rod 95, which goes through hole 43. This clip 94 may be connected by a wire 96, which passes through the hole 48b or down through the alternate wiring openings. The wire 96 is externally connected to the other side of the current supply from the wire 81, so that the lamp may be lighted at all times. The wire 80 may be connected to some form of control device so that the whistle or other accessory is operated when desired.

In the modification shown in Figure 9, the base 97 is made of sheet metal rather than plastic material and one of the openings in the base through which one of the rods such as rod 61 passes is provided with an insulating bushing such as 98. The other rod 60 engages directly with the metal base to provide a return circuit. This metal base construction is shown more in detail in my concurrently filed application above referred to.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A toy building comprising a first part in the form of a supporting base, a second part in the form of an inverted, box-like house body in the form of a plastic molding and having wall-forming portions resting on the base, the house body and base having cooperative elements locating the body in a predetermined position on the base, the wall having a doorway, the body and base having vertically aligned holes, means to secure the body and base together comprising rods extending through the holes and having exposed heads bearing against one of said parts and fastening devices bearing against the other part and each frictionally engaging the other end of the rod, and a door in the doorway, the door having pintles entering recesses in the base and the house body.

2. A toy building comprising a first part in the form of a supporting base, a second part in the form of an inverted, box-like house body made of insulating material and having wall-forming portions resting on the base and an apertured, ceiling-like plate at the top, the body and base having vertically aligned holes, means to secure the body and base together comprising rods extending through the holes and having exposed heads bearing against one of said parts and fastening devices bearing

against the other part and each frictionally engaging the other end of the rod, one of said fastening devices including a wiring clip, a spring member anchored by said wiring clip to the corresponding rod and extending over the aperture in the top plate, a downwardly opening lamp socket carried by and connected to the spring member, a second wiring clip secured to the top plate and connected to the socket, and a lamp in the socket, the spring member being flexible to permit lifting the lamp up through the aperture for replacement.

3. A toy building comprising a base, a plastic molding having four side walls with window and door openings to simulate the side walls of a house, extensions from two such walls to form gables, and a stiffening plate at the top of the side walls, metal rods headed at their lower ends and extending through aligned apertures in the base and the stiffening plate, spring wiring clips having frictional engagement with the upper ends of the rods and bearing on the top of the stiffening plate, a current consuming device carried by the base and connected to the lower ends of the rods, and a readily removable roof-forming member carried by the gable-forming extensions and covering and concealing the wiring clips.

4. In a toy building, a house-like body of molded plastic having walls provided with windows and a ceiling-like plate interconnecting the tops of the walls and having an aperture, wiring clips secured to the top of the ceiling-like plate, a leaf spring secured to one clip and extending over the aperture, a downwardly opening lamp socket secured to the spring and carrying a lamp adapted to interiorly illuminate the toy building, and a return conductor from the socket to the other clip.

5. In a toy building, a molded plastic house body having in the wall thereof a window opening provided along the sides with a discontinuous flange spaced back of the outer face of the wall and reversely beveled ridges on the inner face along the opening, and a window-forming member of differently colored plastic of a size to fit the opening in front of the flange and having yieldable hooks entering the spaces in the flange and engaging the ridges to hold the window-forming member in place.

6. A toy building comprising a first part in the form of an insulating supporting base; a second part in the form of an inverted, box-like house body made of insulating material and having side wall-forming portions resting on the base and an upper horizontal wall spaced from the base to form a room-like chamber; the house body and base having cooperative elements locating the body in a predetermined position on the base, the upper horizontal wall of the body and base having vertically aligned holes; means to secure the body and base together comprising vertical metal rods extending through the holes and the chamber and having exposed heads bearing against one of said parts and providing means for the connection of electrically actuated equipment to the rods, the other ends of the rods being smooth and protruding beyond the other part, and fastening devices slidable along and frictionally engageable with said smooth ends to secure the base and body together, said fastening devices providing means for the connection of electrically actuated equipment to the rods; and a current consuming device carried by the base and connected to the lower ends of the rods.
